VALVE CONSTRUCTION

Robert H. Daisley, Birmingham, Mich., assignor to
 Eaton Manufacturing Company, Cleveland,
 Ohio, a corporation of Ohio

Application May 10, 1939, Serial No. 272,764

4 Claims. (Cl. 123—188)

This invention relates to valves for internal combustion engines and is more particularly concerned with a hollow poppet valve of the so-called sodium cooled type having a relatively high heat conduction metal centrifugally cast in the hollow cavity of the head adjacent the inside of the valve seat portion for rapidly transmitting heat therefrom to the liquid coolant and out the stem portion.

Accordingly the primary object of this invention includes the provision of a hollow poppet valve, preferably of the type containing an internal liquid coolant, having a cast coating of an unlike metal of relatively high heat conducting properties intimately bonded to the hollow cavity of the head adjacent the external seating portion of the valve for the rapid transference of heat from the radially remote sections of the head and seat portion to the main axial body of the coolant and down and out the valve stem portion; the provision in a hollow poppet valve as above described of a centrifugally cast annular ring of copper or the like, intimately bonded to the internal cavity of the hollow head opposite the radially remote external seating portion of the valve.

The above being among the objects of the present invention the same consists in certain novel features of construction, combinations of parts to be hereinafter described with reference to the accompanying drawing, and then claimed, having the above and other objects in view.

In the accompanying drawing which illustrates suitable embodiments of the present invention and in which like numerals refer to like parts throughout the several different views.

Fig. 1 is a vertical sectional view through a hollow poppet valve structure formed in accordance with the present invention;

Fig. 2 is a vertical sectional view of the hollow poppet valve blank of Fig. 1 and enclosing a measured mass of heat conducting element previous to being subjected to a heating operation;

Fig. 3 is a vertical transverse sectional view taken through a suitable furnace showing the valve illustrated in Fig. 2 suitably mounted therein;

Fig. 4 is an elevational view, partially sectioned, of a portion of a suitable type of apparatus for spinning a valve of the type shown in Fig. 1, after it has been suitably heated in a furnace such as shown in Fig. 3, in order to cause a centrifugal distribution of the melted metal contained therein;

Fig. 5 is a view similar to Fig. 1 showing another form of the present invention.

While the invention has been illustrated as embodied in a hollow poppet valve of the type particularly adapted for incorporation in internal combustion engines, it is to be understood that the invention contemplates the use of same in any hollow engine part subjected to a normal operating temperature of several hundred degrees, or wherever it may be found applicable. Referring to the drawing in detail, Fig. 1 illustrates a valve 10 formed from a suitable metal, for example, steel, and comprises a head portion 11 and an integral, axial extending, depending stem structure 12. Hollow valves of the type shown intended to contain sodium or other cooling agent are produced commercially from a single piece of steel by boring out of a solid bar and swaging down the stem portion and upsetting the head structure to suitable dimensions. The lower end of the valve stem 12 is substantially closed except for a small opening 15 provided axially therein for the purpose of later permitting the introduction of a suitable quantity of sodium or other cooling agent into the interior of the valve structure, after which it will be understood that the opening 15 will be securely sealed by a tapered plug 16 against the escape of such material therethrough in a known manner and over the end of the plug 16 an annular tip end of wear-resisting metal 17 is welded thereto to insure against leakage and provides a working surface for a valve tappet head to bear against. The valve head structure 11 is provided with an annular beveled portion forming the valve seating surface 18 and upon which has been deposited a hard surface material for example Stellite. Before or after the lower stem end portion has been swaged down to form the reduced opening 15 a measured amount of an efficient heat conducting or radiating material 21 for example, copper, is introduced in the hollow stem portion. In Fig. 2 there is shown the heat radiating material 21 in the form of rods of measured section which have been inserted through the reduced opening 15, although obviously the material 21 may be supplied in measured amounts before or after the stem end has been swaged to the reduced opening 15, by reducing the material to a suitable granular size depending upon the stem opening.

The type of furnace in which the valve blank shown in Fig. 2 is inserted for the purpose of bringing its temperature to a sufficiently high value to insure melting of the material 21 is

more or less immaterial. In other words, it may be oil or gas fire or any suitable type of electricity furnace, indicated generally at 32 in Fig. 3 being shown as of a gas fired type by way of illustration only. In the broad aspect of the present invention the valve blank illustrated in Fig. 3 may be inserted in the furnace and brought to the required temperature. The temperature to which the valve blank is subjected in the furnace is preferably in the neighborhood of one hundred 10 degrees Fahrenheit in excess of the melting point of the material 21 so as to insure complete fluidity of the material 21 in the furnace, as well as in the subsequent spinning operation. The valve blank may be rotated slowly (mechanism not 15 shown) while being brought up to a suitably high temperature to effect melting of the material 21 and to effect a washing of the melted material against the inner surface of the blank 10 to effect a good bond therewith, and then removed from the furnace and immediately subjected, while the material 21 is still in a molten condition, to a spinning action at high speed about its axis so as to throw the material 21 to the peripheral edges of the space within the head 25 portion of valve blank 10 and to maintain it in such position until it has solidified.

At this stage of the specification it will be well to bring out that the speed of rotation of the valve in the hereinafter described apparatus may be regulated to control the desired area to which the high thermal conductive material 21 may be displaced and the conformation thereof during solidification and bonding to the head blank. If the inverted valve is rotated fairly slow, for example in the order of 150 R. P. M. or less, the material 21 will partially fill the interior peripheral recess radially inward from the external seating surface, while a thin coating will adhere by a combination of conditions including surface tension, inertia, and/or the fluid head against which it works, to the inner, centrally located, surface of the head intermediate the radially remote peripheral recess and thus resist the centrifugal force tending to move the main body of the fluid material 21 radially outwardly. However, if the valve is spun at relatively higher speeds the magnitude of the centrifugal force will overcome the aforementioned conditions tending to resist the complete displacement of the fluid material and will cause the material to densely pack against the inner wall of the external valve seat as shown in Fig. 1. Further, the valve blank may be spun on any preselected axis between the vertical and the horizontal direction for obtaining other variations in the interior surface conformation of the lining of the adjacent area, above mentioned, which it is desired to have thinly coated or lined with the high thermal conductive material 21, depending upon the selected speed of spinning the valve, the depth of lining desired, and the inclination of the axis of rotation to the vertical.

One form of apparatus suitable for effecting this spinning is illustrated in part in Fig. 4 as comprising a frame work generally indicated at 25 positioned in an upright relation. This frame work carries an electric motor 27 arranged with its axis in a vertical relation and the upwardly projecting end of its driving shaft is provided 70 with a hollow cone 29 the interior dimensions of which are sufficient to permit the reception of the head portion of the valve blank therein. Suitably supported above and in axial alignment with the motor 27 by means of a bracket 29 75

secured to the upper end of the frame 25 is an axially shiftable shaft 30 having a tapered pointed end and which is constantly urged in the reduced opening in the end of the valve stem to provide a stem journal and maintain the valve blank in driving relation in cup 29.

With the apparatus thus described a valve blank 10 such as shown in Fig. 4 which has been brought to a suitable temperature as described in a furnace as illustrated in Fig. 3 is removed from the furnace and immediately taken to the apparatus shown in Fig. 4 whereupon the operator presses upward upon the spring pressed shaft 30, which causes the shaft to rise a sufficient distance to permit the head of the valve to be inserted in the hollow cone 29 while the opening 15 in the upper end of the stem 12 is positioned to be received by the pointed end of the shaft 30. The motor is immediately revolved at a sufficient speed to effect the proper centrifugal distribution of the molten material 21 with the blank and the blank is maintained at this speed until sufficient time has elapsed to insure the material 21 having been solidified. The speed at which the motor 27 and consequently the valve is rotated is preferably much greater than that required for simply centrifugally distributing the molten metal 21 in the blank and in valves of ordinary size a speed of 3600 R. P. M. has been found satisfactory. The reason for using this excess speed is to insure that the molten material 21 will be packed under pressure against the internal annular surface within the hollow head portion of the valve, thereby to insure the formation of a more perfect bond and to densify the material 21.

As previously mentioned after the spinning operation is completed and the valve removed, the material 21 will have assumed the condition illustrated in Fig. 1 in which the peripheral portion of the enlarged hollow interior of the head blank opposite the external annular seating portion will be filled by the material 21 which is now intimately bonded to the surface of such portion in the head. It will also be found that the interior 45 surface of this portion of the valve will be smooth and of uniform shape and dimensions preventing localized hot spots due to uneven absorption of heat therethrough.

After the valve blank has reached the condition illustrated in Fig. 4 it may then be machined to bring it to the condition illustrated in Fig. 1 in which it will be observed that those portions of the valve head 11 disposed radially outward of the material 21 has been acted upon to incorporate a wear and corrosion resisting alloy which thus serves to provide a seat or seating surface 19 of the valve. Where a seating alloy material is not applied to those portions of the head 11, above mentioned, then it will be apparent that under such conditions the head portion 18 may itself be machined to provide the desired valve seating surface. If the valve is to be of the sodium filled type or filled with other suitable material such, for example, as disclosed in United States Patent No. 1,670,965, exclusively controlled by applicant's assignee, to improve the cooling properties of the valve, such material may then be introduced into the interior of the valve through the opening 15 previously described, to fill approximately 60% of the hollow interior, and such opening be suitably closed by the plug 16 and sealed by the welded end 17 in accordance with known methods after which the valve may be further acted upon to bring it to its final condition of finish when and if required.

It will be understood that a valve manufactured in accordance with the above disclosure is relatively economical to produce in comparison to previous practices employed in connection with the production of multi-part valves, that a valve formed in accordance with the present invention provides the additional advantage of enabling the hot portions of the hollow head adjacent the valve seating surface to more rapidly dissipate its heat internally to the hollow axial portion of the valve, and that the final product when of the internally cooled type is equally efficient to all intents and purposes as similar types of valves produced from a plurality of pieces of material in accordance with previous practices. The method of forming the valve is not claimed in the present application but is substantially covered in Patent to Charlton 2,183,254, Dec. 12, 1939.

In accordance with the modified valve structure shown in Fig. 5, the valve generally designated 35 comprises a hollow head portion 36 and an integral, axially depending, stem structure having a hollow bore 39, both portions formed from steel bar stock as previously described for the valve of Fig. 1. The upper end of the stem portion 37 is swaged down or otherwise acted upon to form a reduced axial opening 40 into which the tapered plug 41 is fitted and the tip end 42 of hard wear-resisting metal alloy is welded thereto to insure retainer of the plug 41 and prevent leakage of the internal coolant, all as previously described for the valve of Fig. 1 and in accordance with accepted practice. The heat radiating material 46 of lower melting point than the valve 35 is inserted in measured amounts and suitable form through the axial stem opening 41 in any manner previously described for the material 21, of Fig. 2. In the present instance the volume of material 46 is made sufficient to completely fill the hollow cavity of the valve head portion 36. In this structure the filling material of the valve is not spun in but merely brought to temperature in a suitable furnace as shown in Fig. 3 and after the melting point of the material 46 is reached the fluid metal flows to all the interior surfaces of the cavity of the head 36 and becomes intimately bonded to the walls thereof. If necessary in order to secure the proper bond between the filling material 46 and the head 36 a flux may be added or a few drops of alcohol included in the head cavity to resist oxidation, alternatively the operation may be conducted in a reduced or hydrogen atmosphere furnace. Thereafter a suitable drill or boring tool is inserted through the bore 39 of the stem portion and a continuation of the bore 39 is extended to the inside of the head wall 36 by machining or otherwise acting upon the material 46 to produce the axial cavity 48 therethrough. It will thus be apparent that this modification of the invention as shown in Fig. 5 is therefore adapt-

able to the disclosed valve 35 without necessitating the need of special spinning equipment as shown in Fig. 4. Thereafter the valve is acted upon by suitable machine operations to bring the valve to finished size and the annular seating portion 44 of the head 36 is operated upon to provide the desired seat angle and proper concentric relation with the finished stem 37.

Formal changes may be made in the invention from the specific embodiments shown without departing from the spirit or scope of the broad invention which is commensurate with the appended claims.

What I claim is:

1. A hollow metal engine part adapted to operate back and forth rapidly at a normal working temperature of several hundred degrees Fahrenheit, having a closed chamber partly filled with a cooling medium liquid at the operating temperature of said part, portions of said part being subjected to unequal temperature conditions, and a cast metal of high thermal conducting properties integrally bonded to the inner walls of said closed chamber adjacent the portion of highest operating temperature whereby to increase transference of heat from said cast metal to said cooling medium by the turbulent circulation of the medium in a liquid state.

2. A metal valve adapted to operate back and forth rapidly at a working temperature of several hundred degrees Fahrenheit, having a closed chamber therein comprising an integral hollow head portion and an intercommunicating hollow stem portion and containing a cooling medium partly filling said chamber, and a narrow annular ring of cast material of unlike metal having high thermal radiating properties integrally bonded to portions of the interior wall of said hollow head chamber opposite the external seating portion of said valve.

3. A steel valve of the character disclosed comprising an integral hollow stem and head portion defining a closed chamber therein, said head having an external annular seating portion; an annular ring of material of unlike metal having comparatively high thermal conductivity characteristic, cast in said hollow head and integrally bonded to portions of the interior wall thereof opposite said external seating portion.

4. A steel valve of the character disclosed comprising an integral hollow stem and head portion defining a closed chamber therein adapted to contain a liquid coolant, said head portion having an external annular seating surface thereon, and a narrow annular copper ring cast in said hollow head and integrally bonded to the interior surface of the wall thereof opposite said external seating portion, whereby it is wetted and wiped by the liquid coolant to increase the transference of heat from the cast metal to the coolant by the turbulent circulation thereof in the liquid state.

ROBERT H. DAISLEY.
